(57) **CLAIM**

The ornamental design for a set of mantel clips with hanger rod, substantially as shown and described.

DESCRIPTION

FIG. 1 is an isometric left front view of the ornamental design of the set of mantel clips with hanger rod, an isometric right front view is a mirror image, the clips which support the hanger rod are all of identical shape;

FIG. 2 is a cross-sectional view thereof, taken along line 2-2 of FIG. 1, the other end at the same position is a mirror image of the illustration of FIG. 2;

FIG. 3 is a cross-sectional view thereof, taken along line 3-3 of FIG. 1, the other end at the same position is a mirror image of the illustration of FIG. 3;

FIG. 4 is a front view thereof, the opposite side being a mirror image thereof;

FIG. 5 a rear view thereof;

FIG. 6 is a top view thereof; and,

FIG. 7 is a bottom view thereof.

The evenly dashed broken lines in the drawings at the ends of the hanger tube illustrate the portions of the design that form no part of the claimed design. The hanger rod is shown as a tube with a symbolic break in its length, and the appearance of any portion of the hanger rod between the break lines forms no part of the claimed design.

The Display Terminal is shown with a symbolic break in its length. The appearance of any portion of the article between the break lines forms no part of the claimed design.
